(57) **CLAIM**

The ornamental design for a toilet brush head connector, as shown and described.

DESCRIPTION

FIG. 1 is a rear, bottom and left side perspective view of a toilet brush head connector, showing my new design;

FIG. 2 is a front, top and right side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

In the drawings, the broken lines illustrate portions of the article and form no part of the claimed design.
